[57] CLAIM

The ornamental design for a closure for a container, as shown and described.

DESCRIPTION

FIG. 1 is a top plan view of a closure for a container, showing my new design;

FIG. 2 is a top plan view thereof, with the stopper removed;

FIG. 3 is a bottom plan view thereof;

FIG. 4 is a front elevational view of the closure in FIG. 1, the opposite side elevational view being a mirror image thereof;

FIG. 5 is a top right front perspective view thereof;

FIG. 6 is a top right front perspective view thereof, with the stopper in a first alternate position of use;

FIG. 7 is a top right rear perspective view thereof, with the stopper in a second alternate position of use;

FIG. 8 is a left side elevational view of the closure of FIG. 2;

FIG. 9 is a right side elevational view thereof;

FIG. 10 is a cross sectional view thereof, taken along line 10—10 of FIG. 2;

FIG. 11 is a cross sectional view of the closure of FIG. 2, taken along line 11—11 of FIG. 2;

FIG. 12 is a fragmentary enlarged cross sectional view of the closure of FIG. 2, taken along line 12—12 of FIG. 2;

FIG. 13 is a fragmentary enlarged cross sectional view of the closure of FIG. 2, taken along line 13—13 of FIG. 2;

FIG. 14 is a top plan view of the stopper of the closure of FIG. 1 illustrated in isolation for the sake of illustration;

FIG. 15 is a front side elevational view of the stopper of FIG. 14;

FIG. 16 is a bottom plan view of the stopper of FIG. 14;

FIG. 17 is a cross-sectional view taken along line 17—17 in FIG. 14;

FIG. 18 is a left end elevational view of the stopper of FIG. 14; and,

FIG. 19 is a right end elevational view of the stopper of FIG. 14.

The broken line showing of a container in FIG. 4 is for illustrative purposes only and forms no part of the claimed design.
